(57) **CLAIM**

I claim the ornamental design for a banquet ornament, as shown and described.

DESCRIPTION

FIG. 1 is a front perspective view of an embodiment of a banquet ornament, showing my new design;

FIG. 2 is a front elevational view of the embodiment of FIG. 1;

FIG. 3 is a right side elevational view of the embodiment of FIG. 1;

FIG. 4 is a top plan view of the embodiment of FIG. 1;

FIG. 5 is a bottom plan view of the embodiment of FIG. 1;

FIG. 6 is a cross sectional view thereof, taken along lines 6—6;

FIG. 7 is a cross sectional view thereof, taken along lines 7—7; and,

FIG. 8 is a partially cut away front elevational view of the embodiment of FIG. 1, showing the banquet ornament in use. The left side elevational view and the rear elevational view have not been included because they are mirror images of the right side elevational view and the front elevational view, respectively.
